UNITED STATES PATENT OFFICE.

HAROLD R. PINKERTON, OF YAKIMA, WASHINGTON.

CAP-SORTING MACHINE.

Application filed July 31, 1923, Serial No. 654,814. Renewed May 7, 1925.

To all whom it may concern:

Be it known that I, HAROLD R. PINKERTON, a citizen of the United States, and a resident of Yakima, Yakima County, Washington, have invented certain new and useful Improvements in Cap-Sorting Machines, of which the following is a specification.

This invention relates to sorting and packing machines and particularly to machines for sorting bottle caps and for packing them in containers for shipment and from which they may be fed into the magazines of bottle capping machines.

It is the principal object of this invention to provide a machine whereby bottle caps of that character that are adapted to be applied over the mouths of milk bottles, or the like, may be automatically taken from a receiving hopper, into which they are delivered from a bottle cap making machine, sorted and then packed in an even and ordinary manner in tubular containers.

More specifically the invention resides in the means provided whereby caps delivered into each container will be faced in the same direction; that is, all caps will either be right side up or all inverted.

Other objects of the invention reside in the various details of construction and combination of parts whereby a very compact and durable construction is provided and whereby the operation of sorting and packing the caps will be accomplished quickly and accurately.

In accomplishing these and other objects of the invention, I have provided the improved details of construction, the preferred forms of which are illustrated in the accompanying drawings, wherein—

Figure 1 is a front elevation of a bottle cap sorting and packing machine constructed in accordance with the present invention; a part of the hopper being broken away for better illustration.

Figure 2 is a horizontal sectional view taken on the line 2—2 in Figure 1.

Figure 3 is a vertical section taken substantially on the line 3—3 in Figure 2, particularly illustrating the means for transferring the caps to the receiving magazines and the cam actuating mechanism for advancing the caps into the magazines.

Figure 4 is a vertical sectional view taken on the line 4—4 in Figure 1, illustrating the delivery tube leading from the feeding cone within the hopper opening.

Figure 5 is a detailed sectional view illustrating the cap transfer and packing mechanism for caps in upright position.

Figure 6 is a similar view for caps that are inverted.

Figure 7 is a sectional detailed view illustrating the parts, as shown in Figure 5, in a different position.

Referring more in detail to the drawings—

1 and 2, respectively, designate the opposite side members of a supporting frame wherein the sorting and packing mechanism of the machine is contained. These members are joined and are held rigid by means of circular, horizontally disposed frames 3 and 4 that are fixed to the side members or formed integral therewith adjacent their upper and lower ends, as is illustrated in Figure 1. Supported upon the frame is a downwardly tapered hopper 5 with an open upper end into which bottle caps may be delivered for sorting and packing. Usually they are delivered thereto directly from a cap making machine. The hopper has a lower end opening wherein an upwardly tapering feeding cone 6 is rotatably fitted; the said cone being fixed on a supporting or base ring 7 having a transverse bar 8 provided with a hub portion 9 whereby it is fixed upon the upper end of a driving shaft 10 that extends vertically and centrally within the frame and which is mounted for rotation within bearings 11 formed in the horizontal frames 3 and 4. Adjacent its lower end the shaft has a gear wheel 12 mounted thereon through which connection may be made with any suitable driving mechanism.

The feeding cone 6 is hollow, and is provided at one side with a triangular opening 15, through which bottle caps may pass as the cone is revolved, into the interior of the cone from the hopper. The caps, after entering the cone and due to its revolving movement, are finally delivered into the upper ends of one or the other of two downwardly directed tubes 18 and 19 that are supported at opposite sides of the shaft 10 by means of a circular plate 20 that is fixed upon the frame 3 centrally beneath the feeding cone. The lower ends of tubes 18 and 19 terminate slightly above the upper surfaces of a transfer table 25 that is supported horizontally between the frame parts 1 and 2 so that caps that are delivered into

the tubes will be delivered onto the table either top side up, as shown in Figures 5 and 7, or bottom side up, as is shown at the left in Figure 3, but in either case the caps 5 will be advanced about the table from beneath the ends of the tubes by means of the laterally extending ends 26—26' of a rotatably moving feeding spoon 27 that is fixed to shaft 10 in spaced relation to the top of 10 table 25.

Supported from the table 25 about its periphery, at ninety degree intervals are tube holders 30^A and 30^B with open upper ends whereinto cap receiving tubes 31 may be 15 movably mounted. Each of the holders has a side opening 32 flush with the surface of transfer table through which the caps may be advanced from the table into the tube holders.

20 The means which provides for advancing those caps that are delivered onto the table top side up into two oppositely disposed receiving tubes, and those caps that are delivered onto the table bottom side up into 25 the other two receiving tubes will now be described.

After the caps pass from the lower ends 30 of the delivery tubes 18 and 19 onto the table 25 they are engaged by the extending end portions 26—26' of the feeding spoon 27 that is continuously rotated with the shaft 10 and are advanced thereby along the table. It will be stated here that the caps, designated by numeral 28, for which this device 35 is intended, are of that character described in an application now pending in the United States Patent Office under Serial Number 593,256, filed October 9, 1922 and which have a downturned peripheral apron that is 40 adapted to overlap the flange or rim of the milk bottles to which it is applied, and this apron extends somewhat below the plane of the central corking portion of the cap.

45 After the caps have been advanced by the spoon to such position that they are aligned with the openings into the first two tube holders, designated at 30^A in Figure 2, they will be dropped if in "top side up" position, as the cap in Figure 7 is shown, into recesses 35 provided in the table 25 wherein dies 36 are reciprocally contained so that the spoon will then pass thereover and their advance movement discontinued. The dies support rollers 37 at their lower ends that 50 are operable upon an annular cam flange 38 formed on a disk 39 that is fixed horizontally to the shaft 10 below the table 25. The dies are of tubular form and cores 40 are fixed to the table centrally within the dies which 55 have head portions 41 at their upper ends that lie flush with the surface of the table. Springs 42 are coiled about the cores and bear against the under sides of the heads and against upwardly facing shoulders 60 within the dies to thereby yieldingly retain

the latter against upward movement and hold the rollers 37 against the cam flange. The cam is of such form that it will actuate the dies in synchronism with the movement of the spoon upwardly to raise the caps 70 from the opening after the spoon has passed thereover. When in raised position, the upper ends of the dies are flush with the surface of the table and with cores 40 to provide a smooth surface over which the 75 caps may be advanced, as presently described, into the tube holders.

The caps 28 that are delivered from the ends of the tubes 18 and 19 onto the table in "bottom side up" position, on account of 80 their form of construction, will be advanced by the spoon across the die recesses and will finally be brought into contact with guide flanges 45 fixed upon the table whereby they will be crowded outwardly and delivered 85 into the openings of the tube holders 30^B; no special mechanism being required for this transfer.

The means provided for transferring the "top side up" caps from the table 25 into 90 the tube holders 30^A is best illustrated in Figures 2 and 3; the mechanism for feeding each tube being of the same construction and has the same mode of operation. The mechanism for each set comprises a push rod 46 95 slidably held in a guide bracket 47 fixed to table 25, and having a laterally curved, end portion 48 disposed in position to engage with a cap when the rod is moved outwardly to thereby advance the cap from the end of a lifting die into the adjacent tube holder. Mounted upon the bracket 47 is a stud 49 upon which a bell crank is pivotally mounted. A link 50 is pivotally fixed to an arm 51 of the bell crank and with the outer end of 100 the push rod. The other arm 52 of the bell crank is disposed in such position that it will be engaged by a pin 53 fixed in the underside of the spoon in such position that, after the spoon end has passed over the cap and the cap has been lifted by its die, the pin will engage with the end of the bell crank arm 52 to actuate the latter, to move the push rod outwardly and thereby advance the cap into the opening of the tube 110 holder. When the pin slips from the end of the arm 52, a spring 54 that is coiled about stud 49 brings the parts back to normal position.

115 Mounted slidably within the table directly beneath the tube holders 30 are plunger rods 55 provided at their upper ends with plates 56 normally flush with the table top and at their lower ends have rollers 57 that operate on a cam flange 58 formed about the outer periphery of the cam wheel 39. This cam flange is constructed to cause 120 upward movement of the plungers against the retaining pressure of springs 59 that will advance the caps delivered into these 125 130

tube holders, upwardly. Latch plates 60 are fixed pivotally by pins 61 within recesses 62 in the opposite side walls of the tube holders and these have teeth 63 at their inner edges engageable with the caps to prevent them from moving downwardly after being advanced upwardly by the plunger into the tubes. Springs 65 engage with the upper parts of the latches to yieldingly hold them in cap engaging position.

Assuming that the device is so constructed, it is apparent that the caps may be delivered into the hopper in any manner and that, by the rotation of the feeding cone 6, they will be fed properly through the opening 15 into the cone and will then pass downwardly through the tubes 18 and 19 and will be delivered onto the transfer table. Caps that are delivered in "bottom side up" position will be advanced by the spoon until they engage with the guide flanges 45 whereby they will be moved outwardly and into the tube holders 30^B. The other caps delivered in "top side up" position will be advanced by the spoon until they are dropped into the die recesses, thereby permitting the spoon to pass thereover without further advancement. After the spoon has passed, the dies are operated to lift the caps flush with the table surface and they are then advanced, by the push rod mechanism described, into the tubing holders 30^A. The cam 39 operates in synchronism with the other parts to feed the caps in the various tube holders 30 and then upwardly into the tubes 31 which may be removed when filled and from which the caps may be fed into bottle capping machines, or placed in packages for shipment.

Having thus described my invention, what I claim as new therein and desire to secure by Letters-Patent, is:

1. A cap sorting machine of the character described, comprising a receiving hopper, a transfer table, a plurality of tube holders, cap receiving tubes removably supported in said holders, means for feeding caps from the hopper onto the transfer table, a transfer mechanism operable to advance all caps that are delivered onto the table top side up into certain of said tube holders and all caps delivered bottom side up into the other of said holders and means for advancing the caps from said holders into the said tubes.

2. In a sorting machine of the class described, a transfer table, a plurality of packing tubes supported above the table, means for delivering the articles to be sorted onto the table, means operable to deliver articles faced in different ways to the receiving ends of different tubes, means operable to advance the articles upwardly onto the tubes and yieldably mounted latch members for preventing their return movement.

3. A machine of the class described, comprising a transfer table provided with a recess, means for delivering articles onto the table, packing tubes for receiving said articles, a feed spoon operable to advance the articles over said table and to deliver those faced in one direction into said recess, and those faced in an opposite direction into one of said tubes and mechanism for transferring articles from the recess into the other of said tubes.

4. A machine of the class described comprising a transfer table having recesses therein, a hopper, mechanism for feeding caps from the hopper onto the table, a plurality of cap receiving tubes, a revolvably driven feeding spoon operable to advance the caps that are delivered onto the table with a certain face up into certain of said tubes and caps faced the opposite way into said recesses, means operable to periodically lift these caps from the recesses and means for transferring them into other of said receiving tubes.

5. A machine of the class described comprising a transfer table having recesses therein, a hopper, mechanism for feeding caps from the hopper onto the table, a plurality of cap receivers adjacent to the table, a revolvably driven feed spoon operable to engage the cap and to advance them about the table, guide members whereby caps faced in one direction will be directed from the table into certain of said cap receivers and those faced in another direction will be advanced into said recesses and means operable to transfer the latter caps from the recesses into other of said cap receivers.

6. A cap sorting machine of the character described, comprising a frame, a receiving hopper supported by the frame, a transfer table mounted below the hopper and having die recesses therein, delivery tubes leading from the hopper to the table, a feeding means for delivering caps from the hopper into the delivery tubes, tube holders supported adjacent the table, cap receiving tubes removably mounted in said holders, a feeding spoon operable to advance all caps delivered onto the table bottom side up into certain of said tube holders and all caps delivered top side up into the said die recesses, dies operable in said recesses to lift the caps from the recesses and means for transferring these caps into the other of said tube holders and means for advancing caps from the tube holders into the tubes.

7. A cap sorting machine of the character described, comprising a frame, a receiving hopper supported by the frame, a transfer table mounted below the hopper, cap delivery tubes leading from the hopper to said table, a feeding means for delivering caps from the hopper into the delivery tubes, tube holders supported adjacent the table, cap

4

receiving tubes mounted removably in said holders, a rotating feed spoon adjacent the table, guide flanges on the table directed into some of the tube holders and against which caps delivered onto the table bottom side up will be advanced by the spoon and moved thereby from the table into these tube holders; said table having die recesses therein into which all caps delivered onto the table top side up will be advanced by said spoon, dies operable in the recesses, cam mechanism for actuating said dies to lift the caps from the recesses, means operating in synchronism of the spoon for moving the caps after being lifted into the other of said tube holders, and packing means for advancing the caps from the tube holders into the said removable tubes.

8. In a cap sorting machine of the class described, the combination with a transfer table, cap receiving tubes and means for advancing caps delivered onto the table and faced in one direction into certain of said tubes and those faced in an opposite direction into other of said tubes, of a hopper disposed above the table and having a base opening, feed tubes leading downwardly from the said opening to the said table and a hollow feed cone revolvably mounted in said hopper opening and having a side opening through which articles are allowed to pass from the hopper into said feed tubes.

9. A cap sorting machine of the class described comprising a frame, a hopper having a base opening, a transfer table beneath the hopper, cap delivery tubes leading from the hopper opening to the table, tube holders supported to receive caps from the table therein, packing tubes removably mounted in the tube holders, a vertical drive shaft extending centrally through the table into the hopper, a feed cone fixed to the shaft within the hopper opening and operable to feed caps from the hopper into the delivery tubes; said table having die recesses therein, dies reciprocable in said recesses, a feed spoon rotatable with the shaft for moving all caps deliv-

ered onto the table top side up into said die recesses and for moving all caps delivered onto the table bottom side up into certain of the said tube holders, cam mechanism rotatable with the shaft for actuating the dies to lift the caps from the die recesses, feed mechanism for advancing these caps into the other tube holders, plungers mounted in the table beneath the tube holders and cam mechanism for actuating the plungers to feed the caps delivered into the holders upwardly within the packing tubes.

10. A machine as set forth in claim 9, comprising latch mechanism within the tube holders for retaining the caps delivered into the tubes against downward movement.

11. In a machine of the class described, a frame, a hopper supported by the frame and having a base opening, a transfer table supported in the frame beneath said hopper, tubes through which caps may be delivered from the hopper onto the table, a vertical drive shaft extended centrally through the table and into the hopper opening, an upwardly pointed, hollow feed cone fixed to the said shaft within the hopper opening and having a relatively small side opening therein through which caps may pass from the hopper into said delivery tubes, a plurality of tube holders adjacent the table, tubes removably mounted in said holders, a feed spoon fixed on the shaft adjacent the upper face of the table and adapted to advance all caps delivered with a certain face up into certain of said tube holders and all other caps into said table recesses, a cam wheel fixed on the shaft below the table, dies in said table recesses adapted to be lifted by said cam wheel to raise the caps delivered thereto, means for delivering these latter caps into certain of said tube holders, packing members operable by the cam to advance these caps upwardly into the receiving tubes.

Signed at Yakima, Yakima County, Washington, this 6th day of June 1923.

HAROLD R. PINKERTON.
